UNITED STATES PATENT OFFICE.

THOMAS C. JOHNSON, OF NEW HAVEN, CONNECTICUT, ASSIGNOR TO WINCHESTER REPEATING ARMS CO., OF NEW HAVEN, CONNECTICUT, A CORPORATION.

TELESCOPE-SIGHT FOR FIREARMS.

No. 870,295.

Specification of Letters Patent.

Patented Nov. 5, 1907.

Application filed July 1, 1907. Serial No. 381,634.

To all whom it may concern:

Be it known that I, THOMAS C. JOHNSON, a citizen of the United States, residing at New Haven, in the county of New Haven and State of Connecticut, have invented 5 a new and useful Improvement in Telescope-Sights for Firearms; and I do hereby declare the following, when taken in connection with the accompanying drawings and the letters of reference marked thereon, to be a full, clear, and exact description of the same, and which said 10 drawings constitute part of this specification, and represent, in—

Figure 1 a broken view in side elevation of a firearm provided with my improved telescope attachment. Fig. 1^a a detached reverse plan view of the front end of 15 the telescope. Fig. 2 a broken view in side elevation on an enlarged scale of the telescope and the front and rear mountings therefor, a portion of the rear mounting being shown in section. Fig. 3 a view in vertical transverse section through the rear mounting and the gun barrel, a portion of the rear mounting being shown in rear elevation. Fig. 4 a view in vertical transverse section 20 through the front mounting, the ring-portion of the mounting being shown in rear elevation. Fig. 5 a detached view in front elevation on a still larger scale of 25 the rear mounting, stripped. Fig. 5^a a detached view of the friction-spring mounted in the transverse foot of the rear mounting. Fig. 6 a detached right hand edge view of the rear mounting. Fig. 7 a detached plan view thereof. Fig. 8 a reverse plan view thereof. 30 Fig. 9 a detached plan view of the base in which the rear mounting is carried. Fig. 10 a detached view in side elevation of the said base, looking at its right hand side. Fig. 11 a view thereof in end elevation, looking at its rear end. Fig. 12 a view of the chambered 35 micrometer screw and swiveled yoke-like shoe of the rear mounting, the screw being shown in vertical section and the shoe in front elevation. Fig. 13 a detached view partly in vertical section and partly in elevation of the shoe. Fig. 14 a broken view in front elevation, 40 showing the forward edge of the foot of the rear mounting. Fig. 15 a detached view in elevation of the cradle-spring of the rear mounting, looking toward the front end of the said spring. Fig. 16 a view of the said spring in 45 side elevation. Fig. 17 a detached plan view of the dovetail secured to the barrel for the attachment of the rear mounting. Fig. 18 a view thereof in front elevation. Fig. 19 a detached view in front elevation of the 50 front mounting, stripped. Fig. 20 a view thereof partly in side elevation and partly in vertical section. 55 My invention relates to an improvement in telescope sights for firearms, the object being to provide simple, compact, convenient and effective means for mounting a telescope upon a firearm, the said means being constructed with particular reference to ease and accuracy 55 of sighting and compensation for wear, as well as to

avoiding any injury to the telescope owing to the shock of recoil.

With these ends in view my invention consists in the construction and combinations of parts to be herein-after described and pointed out in the claims. 60

In carrying out my invention as herein shown, I employ a telescope 2 which may be of any approved construction. This is supported at its forward end in a front mounting consisting of a guard-ring or band 3 rising from a base 4 having a dovetail slot 5 extending 65 from front to rear, and therefore in the direction of the barrel 6, and receiving a dovetail fastening-block 7 fixed to the said barrel by screws 8 only one of which is shown. A thumb screw 9 in the base 4 provides for adjustably securing the same to the block 7. Within the 70 said base 4 I locate a hollow plunger 10 containing a coiled spring 11 held in position by a pin 12 mounted at its ends in the base 4 and passing through an opening 13 in the plunger which it retains in place, the said opening being enough larger than the said pin to provide for 75 the vertical movement of the plunger. At its upper end the plunger has a doubly beveled nose 14 entering a long groove 15 formed by setting inward the central portion of the lower face of the tube of the telescope at the forward end thereof. Under this construction the 80 telescope is permitted to move longitudinally but is held against rotation. The said spring 11 lifts the said plunger 10, which, acting through its nose 14, exerts a constant effort to press the upper face of the telescope 2 against a bearing surface 16 formed within the upper 85 portion of the ring or band 3. This bearing surface 16 is rounded or convexed from front to rear and concaved from end to end so that it has the effect, as it were, of a line bearing for the telescope, avoiding the indentation or distortion thereof liable to occur, particularly in 90 shooting heavy loads, when point-bearings are used for supporting the telescope, as has heretofore been done. On account of the described form of this bearing it provides a line bearing for the telescope, no matter what the adjustment of the same may be. Thus when the 95 telescope is exactly horizontal and parallel with the barrel the line bearing will be at the point 17 as shown in Fig. 2. In case, however, the telescope is lifted at its rear end the line bearing will move to the rear of the line 17, while if it is depressed at its rear end the line 100 bearing will move to a point in front of the line 17. Furthermore, if the rear end of the telescope is moved to the right or left the line bearing will shift accordingly on the bearing surface 16 which therefore provides a 105 line bearing for the front end of the telescope which bearing automatically accommodates itself, as it were, to the changes in the position of the rear end of the telescope, vertically or laterally, or both, as the case may be.

In order to permit the telescope to rest firmly upon 110

the bearing face 16 on the inside of the ring 3, the same is laterally cut away as at 18 for clearance.

At its rear end the telescope is cradled, as it were, in a cradle-spring 19 formed at its inner end with two coils 20 and terminating in two inwardly inclined rearwardly pitched retaining-ends 21 which are inserted into a pair of correspondingly inclined holes 22 formed in a dovetail rib 23 made integral with and forming a foot for the ring or band 24 of the rear mounting of the telescope.

At its upper end the ring 24 is formed with a crescent-shaped recess 25 for the reception of a yoke-like shoe 26 having its bearing face 27 convexed from front to rear and concaved from end to end, the telescope 15 being pressed upward at its rear end against the said face 27 by the cradle-spring 19 aforesaid. The said shoe 26 is located at the lower end of a stem 28 from which it is separated by a centering bevel 29 which co-acts in accurately centering the shoe with a conical 20 seat 30 formed at the lower end of a micrometer screw 31 chambered for the reception of the stem 28. The said micrometer screw 31 is mounted in an internally threaded hub 32 formed integral with the upper end of the ring 24, this hub, as well as the adjacent portion 25 of the ring, being slotted as at 33 for the purpose of being drawn together by a clamping screw 34 so as to tighten the screw 31 as required, and take up wear. At its upper end the screw 31 carries a knurled thimble 35 the beveled lower end of which fits over the upper 30 end of the hub 32, the said thimble and hub being furnished with graduations which are not shown. The bearing face 27 of the shoe 26 provides by virtue of its peculiar form as described, a line bearing which shifts according to the adjustment of the telescope, 35 while the entire shoe turns upon a vertical axis of the stem 28 to accommodate deflections of the rear end of the telescope to the right or left.

The dovetail rib or foot 23 aforesaid, is arranged laterally with respect to the ring 24 and enters a transverse dovetail groove 36 in the upper face of a base 37 formed in its lower face with a dovetail groove 38 adapting the base to be slipped over a dovetail fastening block 39 having screw holes 39^a and fixed to the top of the barrel by screws 40 one of which is shown in Fig. 3. The said base 37 is provided with a thumbscrew 41 having its end pointed for entrance into a positioning notch 42 located in the left hand side of the block 39 so that in case of the removal of the mount from the gun, it may be replaced thereupon in the exact position which it had thereon before it was taken off.

In order to provide for the lateral adjustment of the rear mounting the foot 23 is formed at its right hand end with a collar 43 to receive the inner end of a micrometer screw 44, the said inner end of which has a groove 45 receiving a pin 46 mounted in the collar 43, whereby the screw is held in place. At its outer end the screw is provided with a knurled, beveled and graduated thimble 47 which fits over and turns upon the outer edge of the said collar 43 which is furnished 55 with a mark 43^a for reading with the graduations on the said sleeve. The inner end of the screw 44 enters an internally threaded sleeve 48 arranged transversely with respect to the base 37 and rising within the center of the dovetail groove in the upper face thereof. At its 60 right hand side the sleeve 48 is cut away to form a clear-

ance space 49 for the reception of the collar 43 aforesaid. The micrometer construction just now described provides for the lateral or "windage" adjustment of the rear mounting.

In order to take up any slack or wear, and to assist in maintaining the mounting without deviation in any of the positions in which it may be set, I form a shallow oblong recess 50 in the front bevel of the foot 23 and in this recess locate a longitudinally bowed spring 51 the crowning central portion of which engages 75 with the front wall of the dovetail 36 in the top of the base 37.

I do not in this case make any claim to the formation of a longitudinal groove in the center of the lower face of the telescope for the reception of the nose of 80 the spring actuated plunger as that will form the subject matter of another application to be filed of even date herewith by Frank F. Burton.

I claim:-

1. The combination with a telescope, of a mounting 85 therefor having a fixed bearing surface convexed from front to rear and concaved from end to end.

2. The combination with a telescope, of a front and a rear mounting therefor, the said front mounting being provided with fixed bearing surface convexed from front 90 to rear and concaved from end to end, and means for adjusting the telescope vertically and laterally at its rear end.

3. The combination with a telescope, of a front and a rear mounting therefor, the latter having a fixed bearing 95 surface convexed from front to rear and concaved from end to end, and means for adjusting the telescope vertically and laterally at its rear end.

4. The combination with a longitudinally movable telescope, of a mounting therefor, and a swiveling bearing 100 shoe located in the mounting and having a bearing surface convexed from front to rear and concaved from end to end.

5. The combination with a longitudinally movable telescope, of a laterally adjustable mounting therefor, a chambered screw located in the top of the said mounting in which it is vertically adjustable, a bearing shoe swiveled in the said screw and providing a bearing for the telescope and means for yieldingly holding the telescope against the said shoe.

6. The combination with a longitudinally movable telescope, of a laterally adjustable mounting therefor, a bearing shoe located within the said mounting and constituting a bearing for the telescope, a chambered micrometer screw for the reception of the said bearing shoe and the vertical adjustment thereof and means for yieldingly pressing the telescope against the said shoe.

7. The combination with a longitudinally movable telescope, of a mounting therefor, an adjusting screw carried by the said mounting, and a bearing shoe mounted in the said screw and provided with a centering bevel coacting with a corresponding bevel in the end of the screw.

8. The combination with a longitudinally movable telescope, of a mounting therefor, a bearing for the telescope, and a transversely arranged cradle-like wire spring to yieldingly lift the telescope against the said bearing.

9. The combination with a telescope mounting, of a spring having its ends inclined rearward and inward for entrance into correspondingly inclined holes in the said mounting, whereby the spring is retained in place.

10. The combination with a longitudinally movable telescope, of a laterally adjustable rear mounting therefor provided at its lower end with a laterally arranged dovetail rib formed in one of its beveled faces with a shallow recess, a base adapted to be secured to a gun barrel and formed with a dovetail groove for the reception of the said rib, and a longitudinally bowed spring located in the said recess and coacting with one of the beveled walls of the said base for taking up slack and wear.

11. The combination with a longitudinally movable telescope, of a rear mounting therefor, a micrometer screw

carried by the said mounting and vertically adjustable therein, a telescope bearing carried by the said screw and partaking of the vertical adjustment thereof, a base adapted to be secured to the gun barrel and carrying the said rear mounting, and a micrometer screw coating with the said rear mounting and base for the lateral or "windage" adjustment of the telescope.

12. The combination with a longitudinally movable telescope, of a mounting therefor, a bearing for the telescope, and a transversely arranged wire spring comprising two retaining arms, and a cross member or reach upon which the telescope rests.

13. The combination with a telescope, of front and rear mountings therefor provided with fixed bearing surfaces convexed from front to rear and concaved from end to end, 15 and means for adjusting the telescope vertically and laterally at its rear end.

In testimony whereof, I have signed this specification in the presence of two subscribing witnesses.

THOMAS C. JOHNSON.
